GARMENT OR IRONING PRESS

Ernest Davis, Syracuse, N. Y., assignor to The Prosperity Company, Inc., Syracuse, N. Y., a corporation of New York

Application April 12, 1927, Serial No. 183,194
Renewed February 23, 1929

11 Claims. (Cl. 68—9)

This invention relates to pressing machines, such as garment and laundry pressing machines, and has for its object a particularly simple and efficient mechanism for closing the press and applying final pressure, and particularly operating means whereby any degree of final pressure can be applied, and also if desired an intermittent slapping action effected.

The invention consists in the novel features 10 and in the combinations and constructions hereinafter set forth and claimed.

In describing this invention reference is had to the accompanying drawings in which like characters represent corresponding parts in all 15 the views.

Figure 1 is a side elevation of a machine embodying my invention.

Figure 2 is a fragmentary plan view of the controlling means for said machine.

Figure 3 is a detail view of the motor mechanism for effecting the preliminary closing of the press, and for applying final pressure.

Figure 4 is a detail plan view of the pressure regulating control lever.

Figure 5 is a sectional view of the pressure regulating valve.

The invention shown in this application is similar in many respects to that disclosed in my co-pending application Ser. No. 181,872, which is 30 sued October 23, 1928, as Patent No. 1,688,918. The claims of the patent are directed to the mechanical construction which includes a pair of motors, one of which may be operated to shift the other as a motion transmitting link, and further includes the mechanical link mechanism by 35 which the mounting of the second motor with respect to the pressing machine frame may be shifted to regulate the pressure exerted by this second motor. The claims of the patent include 40 control mechanism broadly but it is immaterial insofar as the invention covered by the patent is concerned what kind of control mechanism is used, or whether the control mechanism is provided with any means for locking it in operated position.

As distinguished from my Patent No. 1,688,918, the claims of the present application are drawn to novel control mechanism for motors of the type shown in said patent, or other arrangements of 50 the pressing machine motors for applying light and heavy pressure. This application also covers various features of the control mechanism by which the pressure may be regulated by controlling the amount of working fluid admitted to one 55 of the motors, and the feature of the control

mechanism by which a part of the control mechanism locks in operated position.

I have here illustrated my invention as embodied in a conventional type of pressing machine comprising a head 1 movable toward and from a buck 2, mounted upon a suitable bracket or goose neck 3, which in turn is mounted upon a frame 4 of any suitable construction. The actuating or power mechanism for the head 1 comprises pressure operated means and preferably a pair of fluid operated motors arranged to be consecutively operated. In addition to the motor means, the actuating mechanism further includes motion transmitting means, and that here illustrated consists of a lever 5, pivoted between its ends at 60 6 to the frame, and carrying the head 1 on the forward arm thereof, a toggle including links 7 and 8 pivoted together at 9, and respectively to the rear arm of the lever 5, and to the frame at 10, and a power arm or lever 11, which is usually 65 a part of, or integral with, the link 8, this arm 11 being connected to the motor 15. A counterweight 12 is usually mounted on the rear arm of the lever 5 and also one or more countersprings 13, 14 are connected to the rear arm of said lever or to the lever 11. The press thus comprises an 70 actuating mechanism having two step operation; first to partially close the press more or less and second, to more fully close the press under varying degrees of final pressure at the option of the 75 operator.

In the illustrated embodiment of my invention, the power means also includes a second toggle, and a fluid operated motor 21 for straightening the second toggle, and one of the links of the 80 second toggle comprises a cylinder 15 having a piston 16 movable therein, the rod 17 of which is pivoted at 17a to the power lever 11.

The piston is provided with a spring pressed stem 16a projecting in advance thereof and telescoping into the piston rod 17, this stem 16a being a valve which closes the intake port 41a in the head of the cylinder to prevent a sudden starting of the piston and also closes or partly closes said port toward the end of the exhaust stroke to 95 cushion the return movement of the piston. There is another port 16c which is not valve controlled. The valve stem 16a closes or partly closes the port 41a until the piston has started on its power stroke and also closes the port 41a as the 100 piston approaches the end of its in or exhaust stroke. During the finishing of the exhaust stroke the air exhausts through the port 16c. This stem 16a and ports 41a and 16c form no part 105 of this invention.

18 is the other link of the toggle of which the cylinder is a part, the link 18 being mounted on shaft 19 carried by the frame, and at 20 pivoted to the head of the cylinder 15. The fluid operated motor for straightening the toggle consisting of the link 18 and the cylinder 15 comprises a cylinder 21 having a piston 22 movable therein, the cylinder being pivoted at 23 to the frame, and the piston having its rod 24 pivoted at 16 25 to a rock arm 26 mounted on the shaft 19 on which the link 18 is mounted. When motive fluid as compressed air is let into the upper end of the cylinder 15, the piston 16 is actuated and the motion thereof transferred through the parts 11, 15 8, 7 and 5 to bring the head 1 down onto the buck 2, but without pressure or without very much pressure. Thereafter when the motive fluid, as compressed air, is let into the cylinder 21, the piston 22 is actuated to straighten the toggle consisting of the link 18, cylinder 15 and thus apply final pressure. The degree of final pressure applied is controlled by the manually operable pressure regulating valve to be presently described, and the pressure can be alternately applied and relieved to effect a slapping action by a valve mechanism to be presently described.

The means for controlling the flow of fluid to and from the cylinder 15 may be of any suitable form, size and construction, and the construction thereof forms no part of this invention. The valves for controlling the flow of motive fluid to and from the cylinders are so arranged that the valve for controlling the flow of fluid to the motor which effects the final pressure is in series 30 with the valve which effects the preliminary closing of the press whereby the valve which effects the preliminary closing of the press must be first operated. Also, the regulating valve 53 is in the feed line between the cylinders and controls the building up of pressure in the second cylinder 21 after the pressure in the first cylinder 16 is actuated.

The valve means here shown includes a valve casing 28 suitably carried by a bracket on the frame, and connected at one end to a supply pipe 29, which usually has a manually operable cut-off valve 30 therein, a normally closed intake or shut off valve 31 in the casing 28, and also a normally open exhaust valve 32, these valves being connected by a stem 33 whereby they act as a unit, and manually operable mechanism for operating the valve to close the exhaust valve 32, and open the intake valve 31. The intake valve is held closed by a suitable spring 34. The operating means for the valves includes a manually operable element as a button 35 movable in a suitable guide 36, and acting upon one arm of a lever 37, the other arm of which acts on a second lever 38, which presses against a stem 39 of the exhaust valve 32. Obviously when the button 35 has been pressed, the exhaust valve 32 will be closed and the intake valve 31 opened permitting air to enter the valve casing 28 from the pipe 29 past the intake valve 31 and out through the pipe 40 which opens into the casing 28 between the valves 31 and 32. The pipe 40 is connected to an intake passage 41 in the head of the cylinder 15.

When the button 35 is depressed, and held 60 depressed the air enters the cylinder 15 and continues to enter as long as the button 35 is held depressed or until the piston finishes its power stroke. As the piston 16 approaches the end of its power stroke, it uncovers a port 42, so 75 that the pressure within the cylinder passes out

through a pipe 43 to a diaphragm chamber 44 having a diaphragm 45 therein, which acts on a sliding stem 46, the latter acting upon the lever 38. Thus when the piston 16 completes its power stroke, the intake valve 31 is held open and the exhaust valve 32 held closed by the pressure through the pipe 43 to the diaphragm valve 44. In order to relieve the pressure in the cylinder 15 to open the press, the pressure is exhausted from the diaphragm chamber by operating a normally closed exhaust valve 47, located in a casing 48 and having a handle 49 located near the button 35, this handle 49 acting on a stem 50 of the exhaust valve 47. The valve 47 is pressed against its seat by a spring 51 and the valve casing 48 is connected to the pressure side of the diaphragm chamber 44 by a pipe 52. Obviously as the exhaust valve 47 is opened by operating the handle 49, the pressure in the diaphragm chamber 44 will be released permitting the spring 34 to close the intake valve 31 and open the exhaust valve 32, so that the pressure is free to exhaust from the cylinder back through the pipe 40, valve casing 28 and out through an exhaust passage 28a.

53 designates a pressure regulating valve which may be of any suitable form, size and construction. This is suitably supported by the frame as shown in Figure 2 and controls the pressure from the feed pipe 29 to the cylinder 21. It is operated by a manually movable handle 54 and the flow of motive fluid is controlled by a shut off valve carried by the handle 54. This valve is similar to the valve consisting of the casing 28 and combined intake and exhaust valve 31 and 32, and it comprises a casing 55 carried by the handle 54 having a normally closed intake valve 56 therein, a normally open exhaust valve 57 which is connected by a stem 58 to the intake valve 56, a spring 59 acting on the intake valve to hold it closed, and a manually operable member as a lever 60 pivoted at 61 to the handle, and acting upon a stem 62 of the exhaust valve 57, the lever 60 being arranged to be operated by the fingers of the same hand which operates the lever 54. When the valves 56, 57 are in normal position the air is free to exhaust from the cylinder 21 through pipe 21a, casing 55 and space 57a.

The valve casing 55 is connected to the intake pipe 29 through the pressure regulating valve 53 by a pipe 63. The casing 55 is connected to the cylinder 21 by a flexible pipe or hose 21a connected to a nozzle 21b on casing 55. In order that the valve mechanism operated by the button 35 must be first operated to effect the preliminary closing of the press before the final pressure lever is operated, the pressure regulating valve 53 is connected in the pipe 29 in series with the valve casing 28, and as here shown the pressure regulating valve 53 is connected by a pipe 64 to the pipe 40.

The pressure regulating valve is shown in Figure 5. A valve 80 separates the chambers in the valve casing which communicates with the pipes 64 and 63 respectively. The valve 80 is normally held in open position by a spring 82 which is much stronger than a spring 84 which urges the valve 80 into closed position. A diaphragm 86 is connected with the valve 80 and with the spring 82. Pressure in the pipe 63, and the valve chamber communicating therewith, acts against the lower side of the diaphragm 86, through an orifice 88.

When the pressure against the bottom of the

diaphragm 86 reaches a predetermined degree, the diaphragm 86 will be forced upwardly against the tension of the spring 82 and the valve 80 will be moved into closed position.

5 When the pressure in the pipe 63, and the valve chamber in communication therewith, drops below a predetermined degree, the reduction in pressure against the lower side of the diaphragm 86 will permit the spring 82 to move 10 the diaphragm 86 downwardly and open the valve 80 so that working fluid in the pipe 64 may flow past the valve 80 and out through the pipe 63.

The pressure which will cause the valve 80 to close may be regulated by adjusting the tension of the spring 82. This adjustment in the tension of the spring 82 is made by moving the handle 54 which rotates an adjustment member 90, threaded in the top of the casing of the reducing valve 53, and having a flange 92 which presses against the upper end of the spring 82 and maintains the spring 82 under tension. It is obvious that rotation of the adjustment member 90 will cause the adjustment member 90 and disk 92 to move upwardly or downwardly, depending upon the direction of rotation, and thus increase or decrease the compression of the spring 82 so that more or less pressure against the under side of the diaphragm 86 will be required 30 to close the valve 80. This construction of the pressure regulating valve is conventional and forms no part of the present invention.

From the foregoing, it is apparent that the cylinder 15 and piston 16 serve as a connecting rod or link forming part of the motion transmitting mechanism when the press is being closed by the action of the piston 22 in the cylinder 21. That the valves 31, 32 which are operated by the push button 35 are operator operated means 40 for controlling the flow of motive fluid to the cylinders from the feed line 29 and owing to the arrangement of the pipes 40 and 64, the first and second cylinders 13 and 21 are connected in series so that owing to the regulating valve 53 the motive fluid passes first to the cylinder 15 to actuate the piston therein and then to the cylinder 21, the regulating valve controlling or retarding as much as desired, the building up of the pressure in the cylinder 21. The diaphragm chamber 44, pipe 43 and port 42 constitute timed means for locking the valves operated by the push button 35 in their operated position, the timing being effected by the movement of the piston 16 or the closing of the press. The valves operated by the lever 60 control the flow of motive fluid from the regulating valve to the second cylinder 21.

In operation the operator first preliminarily closes the press by depressing the button 35 and holding it depressed until the piston 16 uncovers the port 42, and then to apply any degree of final pressure the operator moves the lever 54 to any desired position while operating the valve handle 60, which controls the flow of fluid to the cylinder 21. The operator can readily determine by the feel of the machine how much pressure is required, and can easily regulate the pressure by moving the handle 54.

In order to control the amount of pressure, means is provided for controlling the flow of fluid to the power means or cylinder 21, comprising a pressure regulating valve having a manual for operating it, this handle or manual being movable into different positions to control 75 the amount of pressure. While the press is

closed by the action of the piston 16 and before the actuation of the piston 22 in the second cylinder 21, the work may be treated in the usual manner by passing a fluid therethrough.

If desired to effect a slapping action on the goods the lever 60 is rapidly operated or "ticked" causing final pressure to be rapidly, alternately released and applied. To open the press, the operator merely operates the handle 49 permitting air to exhaust from the cylinder 15 and also 85 from the pressure regulating valve and the valve chamber 55.

What I claim is:—

1. A pressing machine including cooperating pressing elements, one of which is movable toward and from the other, power mechanism for actuating the movable element including a pressure operated motor, means for controlling the flow of motive fluid to the motor comprising a pressure regulating valve, a handle for operating said valve, a shut off valve for cutting off the flow of motive fluid to the motor, and a second handle carried by the first handle for operating the shut off valve.

2. A pressing machine including cooperating pressing elements, one of which is movable toward and from the other, power mechanism for actuating the movable element to apply heavy pressure comprising a toggle, a fluid operated motor for straightening the toggle, a supply conduit system for supplying motive fluid to the motor, a manually operable pressure regulating valve connected in said system for controlling the flow of motive fluid to the motor, a handle for said valve, and means for controlling the flow of motive fluid from the regulating valve including a valve, a handle for operating the last valve carried by the former handle.

3. A pressing machine including cooperating pressing elements, one of which is movable toward and from the other, power mechanism for actuating the movable element including a toggle, one link of which comprises a cylinder and a piston movable in the cylinder, power mechanism for straightening the toggle including a pressure operated motor, means for controlling the flow of motive fluid to and from the cylinder, and means for controlling the flow of motive fluid to and from the motor comprising a pressure regulating valve having a handle for operating it, and means for controlling the flow of motive fluid to the motor including a valve, and a handle for operating the last valve.

4. A pressing machine including cooperating pressing elements, one of which is movable toward and from the other, power mechanism for actuating the movable element including a toggle, one link of which comprises a cylinder and a piston movable in the cylinder, power mechanism for straightening the toggle including a pressure operated motor, a conduit system for a motive fluid including a motive fluid supply line, means for controlling the flow of motive fluid through the system to and from the cylinder including a manually operable valve connected with the motive fluid supply pipe and with said system, and means for controlling the flow of motive fluid from the conduit system to the motor including a pressure regulating valve connected in the system and having a handle for operating it, a shut off valve connected in the system and arranged to control the flow of motive fluid therethrough to the motor, the shut off valve also having a handle, the shut off valve and the pressure regulating valve being connected 150

in the system between the motor and the first mentioned valve.

5. In a garment or laundry pressing machine, cooperating pressing elements, one of which is movable toward and from the other, mechanism for actuating the movable element including a cylinder, a piston movable in the cylinder, a second cylinder and piston therein connected to the first cylinder to actuate the first cylinder and piston as a unit, a feed line for a motive fluid, piping connecting the feed line to the first cylinder and having a branch connecting it to the second cylinder whereby the motive fluid flows to the first and second cylinders, a first operator-operated valve means in said pipe for controlling the flow of motive fluid through the piping and the branch, a pressure regulating valve in the branch leading to the second cylinder, and a second operator-operated valve means in the branch for controlling the flow of motive fluid from the pressure regulating valve to the second cylinder.

6. In a garment or laundry pressing machine, cooperating pressing elements, one of which is movable toward and from the other, mechanism for actuating the movable element including a cylinder, a piston movable in the cylinder, a second cylinder and piston therein connected to the first cylinder to actuate the first cylinder and piston as a unit, a feed line for a motive fluid, piping connecting the feed line to the first cylinder and having a branch connecting it to the second cylinder whereby the motive fluid flows to the first and second cylinders, a first operator-operated valve means in said piping for controlling the flow of motive fluid through the piping and the branch, means controlled by the operation of the machine by the first cylinder and piston for locking said first operator-operated valve means in its operated position, release means for the locking means, a pressure regulating valve in the branch leading to the second cylinder, and second operator-operated valve means in the branch for controlling the flow of motive fluid from the regulating valve to the second cylinder.

7. In a garment or laundry pressing machine, cooperating pressing elements, one of which is movable toward and from the other to close and open the press; mechanism for actuating the movable element including a cylinder, a piston movable in the cylinder, motion transmitting members between the cylinder and the movable pressing element, a second cylinder having a piston therein, connecting means between the second cylinder and the first cylinder through which the second cylinder actuates the first cylinder and piston as a unit; a feed line for a motive fluid including a conduit system connecting the first and second cylinders; a pressure regulating valve in the conduit system between the cylinders; normally closed operator-operated valve means for controlling the flow of motive fluid to and from the first and second cylinders; means controlled by movement of the actuating mechanism into closed position for locking the valve means in its operated position, and a manually operated valve in the feed line to the second cylinder for controlling the flow of motive fluid from the regulating valve to the second cylinder.

8. In a garment or laundry pressing machine, cooperating pressing elements, one of which is movable toward and from the other to close and open the press; motor means for actuating the movable element including a first and second

cylinder and piston motor to close the press and apply heavy pressure respectively, a feed line for a motive fluid with connections to the cylinders through which the motive fluid passes to the first and second cylinders; a valve in the line leading to the second cylinder for regulating the degree of working fluid pressure supplied to the second motor; operator-operated valve means in the feed line for controlling the flow of fluid to the first cylinder and the regulating valve; means controlled by the movement of the actuating mechanism into closed press position for locking the operator-operated means in its operated position; means for releasing the locking means; and a second operator-operated valve in the line leading to the second cylinder for controlling the flow of motive fluid from the regulating valve to the second cylinder.

9. In a garment or laundry pressing machine, cooperating pressing elements, one of which is movable toward and from the other to close and open the press; motor means for actuating the movable element including a first and second cylinder and piston motor to close the press and apply heavy pressure respectively; a feed line for a motive fluid with connections to the cylinders through which the motive fluid passes to the first and second cylinders; a valve in the line leading to the second cylinder for regulating the degree of working fluid pressure supplied to the second motor; operator-operated valve means in the feed line for controlling the flow of fluid to the first cylinder and the regulating valve; a handle for operating the regulating valve to vary the pressure supplied by said valve; a manually operated valve in the feed line to the second cylinder for controlling the flow of fluid from the regulating valve to the second cylinder; and a handle for the last named valve carried by the handle of the regulating valve.

10. In a garment or laundry pressing machine, cooperating pressing elements, one of which is movable toward and from the other to close and open the press; mechanism for actuating the movable element including a cylinder, a piston movable in the cylinder, motion transmitting members between the cylinder and the movable pressing element, a second cylinder having a piston therein, connecting means between the second cylinder and the first cylinder through which the second cylinder actuates the first cylinder and piston as a unit; a feed line for a motive fluid including a conduit system connecting the first and second cylinders; a pressure regulating valve in the conduit system between the cylinders; normally closed operator-operated valve means for controlling the flow of motive fluid to and from the first and second cylinders; means controlled by movement of the actuating mechanism into closed position for locking the valve means in its operated position, and a manually operated combined intake and exhaust valve in the feed line to the second cylinder operable into one position to admit motive fluid from the regulating valve to the second cylinder and operable into another position to exhaust the motive fluid from the second cylinder.

11. In a garment or laundry pressing machine, cooperating pressing elements, one of which is movable toward and from the other to close and open the press; motor means for actuating the movable element including a first and second cylinder and piston motor to close the press and apply heavy pressure respectively, a feed line for a motive fluid with connections to the cylinder

ders through which the motive fluid passes to the first and second cylinders; a valve in the line leading to the second cylinder for regulating the degree of working fluid pressure supplied to the second motor; operator-operated valve means in the feed line for controlling the flow of fluid to the first cylinder and the regulating valve; means controlled by the movement of the actuating mechanism into closed press position for locking 10 the operator-operated means in its operated po-

sition; means for releasing the locking means, and an operator-operated combined intake and exhaust valve in the line leading to the second cylinder, operable into one position to admit motive fluid from the regulating valve to the second cylinder and operable into another position to exhaust the motive fluid from the second cylinder. 80
